UNITED STATES PATENT OFFICE

131,408

DESIGN FOR A SOCK

Jean Harms, Clayton, Mo.

Application May 7, 1941, Serial No. 100,821

Term of patent 7 years

To all whom it may concern:

Be it known that I, Jean Harms, a citizen of the United States, residing at Clayton, county of St. Louis, State of Missouri, have invented a new, original, and ornamental Design for a Sock, of which the following is a specification, reference being had to the accompanying drawing, forming part thereof.

Fig. 1 is a perspective view of one side of a sock showing my new design, and

Fig. 2 is a perspective view of the opposite side thereof.

The sock illustrated is for the left foot, the opening in the toe portion being disposed to permit the protrusion of the great toe.

I claim:

The ornamental design for a sock, as shown and described,

JEAN HARMS.
